US00D537292S

(12) **United States Design Patent** (10) **Patent No.:** **US D537,292 S**
Beesley et al. (45) **Date of Patent:** **** Feb. 27, 2007**

(54) **HAND MIXER**

(75) Inventors: **Brian K. Beesley**, Draper, UT (US);
Eric Hales, Ogden, UT (US); **Liao Zhiwen**, Foshan (CN)

(73) Assignee: **Back to Basics Products, Inc.**,
Bluffdale, UT (US)

(**) Term: **14 Years**

(21) Appl. No.: **29/251,615**

(22) Filed: **Jan. 9, 2006**

(51) **LOC (8) Cl.** **31-00**

(52) **U.S. Cl.** **D7/379**

(58) **Field of Classification Search** D7/376-386,
D7/412-414, 665; 99/509-511; 241/30-37.5,

(57) **CLAIM**

The ornamental design for a hand mixer, as shown and described.

DESCRIPTION

FIG. 1 is an elevated, perspective view of the hand mixer in accordance with our invention;

FIG. 2 is a front elevational view thereof;

FIG. 3 is a rear elevational view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in FIGS. 1-7 are for illustrative purposes only and form no part of the claimed design.

1 Claim, 6 Drawing Sheets
